F. BANIA

IRONING BOARD

Filed Jan. 30, 1922

Inventor

Frank Bania

By *Bartholomew Bania*

Attorney

UNITED STATES PATENT OFFICE.

FRANK BANIA, OF DETROIT, MICHIGAN.

IRONING BOARD.

Application filed January 30, 1922. Serial No. 532,623.

To all whom it may concern:

Be it known that I, FRANK BANIA, a citizen of Poland, residing at Detroit, in the county of Wayne and State of Michigan, have invented certain new and useful Improvements in Ironing Boards, of which the following is a specification, reference being had therein to the accompanying drawings.

This invention relates to foldable furniture and more particularly to tables or ironing boards and its object is to provide a foldable supporting structure adapted to form, in extended condition, a rigid support for the table or board.

15 A further object is to provide a supporting structure for devices of this class wherein the structure includes a base member adapted to rest directly upon the floor and provide an extended surface to contact the floor.

20 It is also an object of the invention to provide a supporting frame work or structure which may be conveniently and quickly folded into a small space and when extended, will rigidly support the ironing board in such a manner as to leave an extended free portion to the board.

25 A further object is to provide simple and convenient means for supporting, in an elevated position above the ironing board, an electric cord in such a manner as to permit of a free movement of an electric iron to which the cord is connected, over the entire surface of the ironing board without putting undue strain upon the cord or permitting the cord to at any time come into contact with articles being ironed upon the board.

30 With the above and other ends in view, the invention consists in the matters herein-after set forth and more particularly pointed out in the appended claims, reference being had to the accompanying drawing in which—

40 Fig. 1 is a perspective view of a device illustrative of the invention and showing the same in operative position;

45 Fig. 2 is a side elevation of the same; and

Fig. 3 is a side elevation showing the device in partly folded condition.

50 In the drawing, 1 indicates the ironing board which is of the usual form and is supported upon a foldable supporting structure which is pivotally connected to the underside of the board and arranged to fold against said side. This supporting structure comprises a rectangular base frame 2 to

55 which a pair of legs 3 is pivotally attached.

At the lower ends of the legs a bar 4 extends across the frame 2 adjacent one side of the legs 3 to prevent said legs from turning in one direction, said bar forming an abutment against which the legs rest or in contact with which said legs come as they are turned upwardly upon their pivotal connection 5 with the base 2. A pair of legs 6 is pivotally attached at one end, as at 7, to a cross-member 8 secured to the underside of the board 1 intermediate its ends, and these legs 6 are connected adjacent their free ends by a cross-bar 9. When the frame is in extended or operative position, the legs 6 are engaged with notches 10 in the side members of the base frame 2, extending downwardly and forwardly in an inclined position from the lower side of the ironing board in such a manner as to form diagonal brace members.

75 Pivottally attached to the legs 3 intermediate their ends is a pair of links 11 or diagonal bracing members, which members are pivotally attached, as at 12, to a cross member 13 secured to the underside of the ironing board adjacent one end thereof. A cross bar or cleat 14 is secured to the underside of the ironing board adjacent the cross member 8 to which the legs 6 are pivotally attached, said members 8 and 14 being spaced apart just sufficiently to receive the free ends of the legs 3 between them. When the frame is in set up condition, the legs 3 are in a substantially vertical position with their upper ends engaged between the cross member 8

80 and cleat 14 on the under side of the ironing board and the legs 6 which are pivotally attached to the cross member 8 are engaged at their lower ends with the notches in the base frame 2, extending downwardly and forwardly at an inclination from the lower side of the board and from substantially the upper ends of the legs 3 so that the legs 3 and 6 and the base 2 provide a substantially triangular frame. The rearwardly projecting end of the ironing board is supported by the diagonal brace or link members 11 which extend downwardly and forwardly from the rear end of the board to their point of pivotal attachment with the legs 3 intermediate the ends thereof.

100 The supporting structure thus formed provides a very rigid frame when in operative position to rigidly support the ironing board with an extended free end portion of

- the board projecting beyond the point at which the supporting frame is attached to the board so that articles of clothing may be slipped over this projecting end of the ironing board and the frame structure will not interfere therewith. The rectangular frame 5 forms an extended base to rest upon the floor and gives a firm, rigid and extended bearing for the frame so that the ironing board, when in operative position will be 10 rigidly supported without the necessity for attaching it to a wall or other fixed portion of the building in order to give it rigidity and prevent wobbling while it is being used.
- 15 The arrangement of the legs permits of folding of the several parts, one upon the other, so that the base 2 is brought adjacent the underside of the board when the supporting structure is in folded condition, and the 20 connection of the legs and base to the ironing board by the brace members holds the parts connected and in operative position so that they may be quickly and easily extended into supporting position.
- 25 In the use of the electric flat iron 15 to which an electric conductor or cord 16 is attached, the cord is drawn back and forth as the iron is moved over the table in use and is quite liable to soil the articles being ironed 30 by coming in contact therewith. Further, the constant bending of the cord by the movement of the flat iron to and from over the table causes the cord to break and a short circuit of the electric current is often 35 caused thereby. To flexibly and yieldingly support this cord 16 at a suitable distance from its attachment to the flat iron so that it may be freely moved back and forth over the ironing table, but will be supported or 40 suspended at all times so that it cannot come in contact with the articles being ironed, a flexible supporting arm or bracket 17 is provided, said arm comprising a wire of heavy gauge, which wire adjacent one end is 45 formed into a loop or coil 18 and the end portion of the wire beyond the coil is bent to form a U-shaped supporting end portion 19 adapted to be engaged within a suitable socket or hole in the end of the ironing board. The free end of the wire 17 is provided with suitable means, such as a clip 20 to engage the electric rod 16. The cord is therefore suspended at a considerable height above the ironing table and a free movement 50 of the flat iron is permitted due to the free yielding movement of the arm, the coil 18 providing this yielding or spring action. When the flat iron is moved toward the opposite end of the table 55 the pull on the cord will flex the supporting arm, and as the iron is moved toward the opposite end of the table, the arm will straighten out and take up the slack in the cord. The cord is therefore prevented from 60 coming into contact with the surface of the 65 table and is held against kinking or bending to such an extent as will cause the cord to break. When the ironing board is folded, this cord support may be slipped from its socket in the end of the board so that it will 70 not interfere with the compact folding of the board.
- While a specific construction and arrangement has been illustrated and described, it is obvious that the construction and arrangement of parts may be varied within the scope of the appended claims without departing from the spirit of the invention and I do not therefore limit myself to the particular form or arrangement shown.
- Having thus fully described my invention, what I claim is:—
1. A structure of the character described wherein an ironing board is supported by a foldable frame, said frame comprising a base frame, vertical legs pivotally attached at their lower ends to the base frame to swing downwardly into said frame, a transverse cleat on the lower side of the ironing board intermediate its ends, a transverse pivot member secured to the side of the ironing board in spaced relation to the cleat, said space being adapted to receive and detachably hold the upper ends of the vertical legs, diagonal legs pivotally attached at 90 their upper ends to the pivot member to swing into parallelism with the lower side of the board and adapted to detachably engage the base frame at their lower ends when the foldable frame is in extended position, 95 and links pivotally attached at one end to the underside of the ironing board adjacent the ends thereof and at their opposite ends to the vertical legs intermediate the ends of said legs to pivotally connect the ironing 100 board to the vertical legs to fold therewith.
2. A structure of the character described and wherein an ironing board is supported by a foldable frame, said frame comprising an open rectangular base frame having a 110 transverse bar intermediate its ends, vertical legs pivotally attached to the base frame adjacent said transverse bar, said bar forming an abutment for said legs when in vertical position and said legs being adapted to 115 turn upon their pivotal connection with the base frame downwardly into said frame, links pivotally attached to said vertical legs intermediate their ends, said links being pivotally attached at their upper ends to the 120 underside of the ironing board adjacent one end thereof, said links being adapted to swing upon said legs and bring the base frame toward the underside of the ironing board when the legs are folded into the base 125 frame, a transverse cleat on the underside of the ironing board, a pivot member secured to the underside of the ironing board with a space between said member and cleat, said space being adapted to receive and hold the 130

upper ends of the vertical legs when said legs are in extended position, and diagonal legs pivotally attached at their upper ends to said pivot member to swing into parallelism notched to detachably engage the lower ends 10 of the diagonal legs.

In testimony whereof I affix my signature in presence of two witnesses.
